CLAIM

We claim the ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a second embodiment thereof. The broken lines in the drawings illustrate portions of the graphical user interface and form no part of the claimed design.

The dot-dash broken lines in the drawings illustrate a display screen or portion thereof and form no part of the claimed design.
